UNITED STATES PATENT OFFICE.

JOHN W. RAMSEY, OF BEAVER FALLS, PENNSYLVANIA, ASSIGNOR OF ONE-HALF TO JOHN CORBUS, OF SAME PLACE.

PRESSURE-REGULATOR.

SPECIFICATION forming part of Letters Patent No. 361,082, dated April 12, 1887.

Application filed January 27, 1887. Serial No. 225,698. (No model.)

To all whom it may concern:

Be it known that I, JOHN W. RAMSEY, a citizen of the United States, residing at Beaver Falls, in the county of Beaver and State of Pennsylvania, have invented certain new and useful Improvements in Pressure-Regulators; and I do declare the following to be a full, clear, and exact description of the invention, such as will enable others skilled in the art to 5 to which it appertains to make and use the same, reference being had to the accompanying drawing, and to the letters and figures of reference marked thereon, which form a part of this specification.

15 The figure presents a central sectional view of a fluid-pressure regulator to which I have applied my improvements.

The object of my present invention is to provide a pressure-regulator, which is adapted 20 for use in connection with gas, steam, water, or other fluid apparatus, for the purpose of regulating the fluid-supply or reducing the same from a high pressure to any desired degree.

25 The drawing shows a particular form of regulator, which is particularly designed to reduce the pressure in gas-mains to any predetermined low pressure which is desired.

In the drawing, *a* represents a low-pressure 30 pipe, open at both ends.

b is a T-connection, upon which the pressure-reducing valve is located.

c is another T-connection, upon which the regulating-diaphragm is located.

35 *d* is the valve-casing of the pressure-reducing valve.

e is the high-pressure inlet of the valve.

f is an annular opening in the valve-chamber, in communication with opening *e*, and 40 also with the interior chamber, *g*, of the valve, through the annular slot or channel *h*.

i is a valve-seat above channel *h*, and *k* is a similar seat below the channel. Seats *i* and *k* are of different areas, and the valve *l*, which 45 works thereon, has two seats, *m* and *n*, of corresponding areas.

o o are packing-rings on the valve-seats, of any suitable material.

Valve *l*, below the valve-seats *m* and *n*, is

cone-shaped, and the valve itself has a central 50 longitudinal passage through it. *p* is the valve-stem of valve *l*. It is secured centrally of the valve in a spider-frame, *q*, arranged across the opening therein. The other end of the valve-stem passes up through a stuffing- 55 box, where it is pivoted to a rock-lever, *r*, fulcrumed in the end of the post *s*, cast on the valve-chamber.

t is a diaphragm, exposed to the pressure of the fluid in the low-pressure pipe *a*. *u* is the 60 diaphragm-chamber, formed of two dish-shaped castings placed face to face and bolted together.

The elastic diaphragm *t* is secured between two disks, one of which has a slotted stem, *v*, 65 and projects through a central aperture in the diaphragm-chamber. To the upper end of this stem the other end of the rock-lever *r* is pivoted. The stem *v* passes through a hole in the yoke or bail *w*, which is secured or 70 formed on the diaphragm-chamber *u*.

x is a lever pivoted to a projection, *y*, of the chamber *u*, and passes through a slot in the stem *v*. It is provided with the usual sliding weight. The lever *x* bears upon the stem *v* 75 and depresses the diaphragm *t* with a varying pressure, due to the position of the weight upon the lever.

z is a pipe leading from the low-pressure pipe *a* to the diaphragm-chamber *u*, and is 80 provided with a valve.

1 is a pressure-indicator for the high-service pressure, and 2 is a pressure-indicator for the low-service pressure.

The operation of my device is as follows: 85 Upon gas being introduced into the valve-chamber, the valve *l* rises and allows the pressure to be transmitted into the low-pressure pipe. Instantly upon the high pressure being admitted to pipe *a* the diaphragm *t*, in 90 communication therewith, is acted upon by the pressure, and it rises and rocks the lever *r*, pivoted to the valve-stem of valve *l*, with a pressure tending to close said valve. The area of the diaphragm greatly exceeding the 95 area of the valve *l*, the low pressure in pipe *a* thereby compensates for the pressure in the high-service pipe. By means of the sliding

weight on lever x the force exerted by the diaphragm t is caused to vary, so as to graduate the opening in the regulating valve, whereby any desired low pressure may be had in pipe a , independent of the varying pressure in the high-service pipe.

The purpose of the pipe z is as a substitute for pipe c . When so used, the diaphragm-chamber casting is not bored out, so as to communicate with pipe c , but is left solid and imperforate. The valve in pipe z is employed to graduate the admission of the gas or vapor, so that the regulator will work when very low pressures are desired in pipe a .

By the employment of the two levers r and x a compensating or balancing device of marked sensitiveness or responsiveness is produced. Acting conjointly, as they do, they constitute a compound lever and admit of a smaller sliding weight being used than is pos-

sible where a single weighted lever is used. These results are highly desirable in a fluid-pressure regulator.

Having described my invention, what I claim as new, and desire to secure by Letters Patent of the United States, is—

In a pressure-regulator, a diaphragm, a diaphragm-stem, a weighted lever arranged to bear upon said stem, a regulating valve and stem, a rock-lever fulcrumed at an intermediate point and pivoted at the one end to the valve-stem and at the other to the diaphragm-stem, and pipe-connections between the valve and diaphragm, all in combination.

In testimony whereof I affix my signature in presence of two witnesses.

JOHN W. RAMSEY.
